UNITED STATES PATENT OFFICE.

MADS M. LARSEN, OF COLTON, CALIFORNIA.

SHADE BRACKET AND CURTAIN ATTACHMENT.

Application filed November 22, 1923. Serial No. 676,317.

To all whom it may concern:

Be it known that I, MADS M. LARSEN, a citizen of the United States, residing at Colton, in the county of San Bernardino and

5 State of California, have invented new and useful Improvements in Shade Brackets and Curtain Attachments, of which the following is a specification.

My present invention being referred to as 10 a shade bracket and curtain attachment, it may be understood that it is an object of this invention to provide simple and effective means for the support of a shade bracket, the supporting means referred to being 15 preferably of such character as to permit the optional attachment thereto of a curtain rod, the entire supporting organization referred to being preferably such as to permit of an adjustment of one or both of a pair of shade 20 brackets, to adapt the same to the predetermined length of a shade roller, without necessitating any change in the position of a primary supporting element which may be secured to a wall, or to a window jamb, or to 25 a window frame, or to any other suitable fixed or movable vertical or inclined surface.

It is a further object of this invention to provide a shade support requiring the insertion of but a single screw at or near each end 30 of a window shade or a curtain rod; and, in a preferred embodiment of my invention, the mentioned single screw may be adapted to support both a shade-engaging bracket and a curtain rod, both the shade bracket and the curtain rod being moreover independently adjustable relatively to a primary support secured to a wall, or the like.

It is a further object of this invention to 40 provide a shade support which may consist essentially of a wall element comprising an upright stud and a removable shade bracket comprising a sleeve or sleeves adapted to extend over said stud; and, in a preferred embodiment of my invention, the mentioned 45 stud and the sleeve adapted to interfit therewith may both be non-circular in cross section, one advantageous embodiment of my invention comprising a wall element comprising a body having a nick at one end and at its opposite end a flat face or shoulder from which extends a threaded element adapted to enter a wall, or the like, the said body being provided also with a squared stud extending substantially at right angles to the mentioned threaded element and adapted to interfit with any one of a plural-

ity of sleeves which may be integral with a shade-engaging bracket, the said sleeves being preferably arranged in a linear series extending substantially at right angles to said bracket, in such manner that any one of the mentioned sleeves may be fitted over the described stud and retained thereon by gravity.

It is a further object of this invention to 50 associate with the described shade-supporting elements a curtain rod which may consist essentially of interfitting elements sleeved together and provided at or near their ends with squared or other non-circular studs projecting downwardly and adapted to interfit with any one of the mentioned sleeves of a shade supporting bracket of my novel design, the construction referred to being such as to permit of the support of a shade or a curtain, or both a shade and a 55 curtain, from a single pair of studs each integral with a single screw, the screws constituting a pair and being arranged either in parallel planes extending at right angles to a wall or in the same plane parallel with a 60 wall or the like, or with a shade or rod supported therefrom, both the shade and the curtain being normally retained by gravity and securely held but nevertheless conveniently removable by a substantially vertical 65 movement.

Other objects of my invention will appear from the following description of a preferred embodiment thereof, and from the appended claims, taken in connection with the 70 accompanying drawings, in which:

Figure 1 is a perspective view showing my novel shade brackets and curtain attachment secured to a single substantially vertical surface.

Fig. 2 is a top plan view of the supporting elements shown in Figure 1, with parts broken away to indicate rod sections sleeved together in a known manner and to show primary wall engaging supports retained by 80 threaded means.

Fig. 3 is an elevational view substantially on the line 3—3 of Figure 2.

Fig. 4 is a detail view showing in perspective a preferred form of primary supporting 105 or wall element suitable for use in connection with a shade bracket of the general character shown in Figure 5.

Figs. 5 and 6 are, respectively, perspective views of a pair of brackets suitable for use 110 at opposite ends of a shade roller.

Fig. 7 is a perspective detail view of a

portion of a curtain rod provided with a depending stud adapted to extend within one of the sleeves comprised in my respective shade brackets.

5 Fig. 8 is a horizontal sectional view employed merely to emphasize the practicability of securing my novel wall elements or primary supports in either of two positions at right angles to one another.

10 Referring to the details of that specific embodiment of my invention which I have chosen for purposes of illustration, 1 may be a substantially vertical section on a window frame, window "trim," or the like, to which 15 a roller shade 2, or a curtain rod 3, or both a shade and a curtain rod, are to be secured; and my novel supporting organization comprises a primary support of the general character best shown in Figure 4, this support 20 preferably consisting of a body 4, from which may project a threaded element such as a wood screw 5, shown as provided at '6 with a nick to permit the attachment of the same and with an upstanding squared stud 7, 25 all of the parts referred to being preferably in the form of an integral casting of brass or similar material.

A pair of primary supports of the general character shown in Figure 4 may be secured 30 at a uniform height either to a single flat surface or to substantially parallel vertical surfaces, such as the inner faces of a window frame, and great care need not be taken that the distance between the upstanding studs 7 35 of a pair of such supports is exactly equal to the length of a shade roller to be supported therefrom, for the reason that I propose to associate with the mentioned primary supports or wall elements 4 a pair of shade-engaging elements 8, 8', of the general character 40 best shown in Figures 5 and 6, from an inspection of which it will be understood that each of these elements consists essentially of a bracket 9 or 9' (one of these being 45 adapted to engage a round pin and the other being slotted to receive the squared or "spring" pin of an ordinary shade roller) integral or otherwise provided with a linear series of sleeves 10, arranged substantially at 50 right angles to the shade engaging portions of the brackets 9, 9', and adapted to extend over and variably to interfit with studs 7, a sufficient number of the sleeves 10 being employed to permit a reasonable range of 55 adjustment in the direction of the length of a shade roller and the described construction being such as to permit of the supporting of a shade roller entirely from two screws, or their equivalent, entering the wall or walls, 60 directly beneath the squared studs from which a roller is supported and in such manner as to permit it to be removed or replaced, in a suitably adjusted position, by a simple vertical movement.

65 There being a plurality of substantially

parallel and substantially vertical sleeves comprised in my respective shade engaging elements, I may take advantage of this construction to provide means for supporting therefrom, and indirectly from the single 70 pair of screws referred to, the curtain rod 3, my preferred construction for this purpose comprising a curtain rod formed of interfitting sections 11 and 12, shown as sleeved together and as rebent in such manner that a curtain supported therefrom may substantially cover a window shade, the rebent ends of the respective sections being preferably provided with depending squared studs 13 integral therewith or secured thereto in a 75 manner adapting the same to enter any preferred unoccupied pair of sleeve openings in the intermediate or shade-engaging elements 8, 8', whose respective linear series of sleeves thereby afford adequate and convenient 80 means for adjustably and removably supporting the respective ends of a curtain rod, it being obvious that the curtain rod herein shown is more suitable in connection with primary supports 4 positioned as shown at 90 A in Figure 8, although only an obvious shortening of the straight return section or shank 14 of a rod, or a slight elongation of the body 4 of the primary supporting or 95 wall element would be necessary to adapt the same to use in the position shown at 13, Figure 8; and it is an advantage of my described construction, presented merely as illustrating the scope and possibilities of the 100 present invention, that it is adapted to support, either with or without a window shade, either a single curtain rod or a plurality of rods, which may be positioned at the same level or at various levels and preferably slightly above a shade roller in connection with which they may be used, it being a current custom to employ a pair of rods respectively supporting a curtain and a drape relatively in front of and slightly above a window shade.

110 Although I have herein described but one complete embodiment of my invention, it will be understood that various features thereof might be independently employed, and also that various modifications might be made therein without departure from the spirit and scope of my invention, as the same is indicated above and in the following claims.

115 What I claim is:

1. In a shade support, a wall element comprising a screw and an upstanding square stud adapted to interfit with a shade engaging element vertically slideable thereon, and a shade-engaging element slidably mounted thereon and comprising a sleeve adapted selectively to interfit with said stud, said shade-engaging element being provided with a plurality of square sleeves 120 arranged in a linear series.

2. In a shade support, a wall element comprising an upstanding square stud adapted to interfit with a shade engaging element vertically slideable thereon, and a shade-engaging element slidably mounted thereon and comprising a sleeve adapted selectively to interfit with said stud, said shade-engaging element being provided with a plurality of square sleeves arranged in a linear series 5 and adapted to interfit either with a stud upon a primary support or with a depending stud upon a curtain rod.
3. In a shade support, means for supporting one end of the shade directly above a single screw, said supporting means comprising a body provided with a nick at one end and with a screw thread at the other and a squared stud extending at right angles from said body.
4. In a shade support, a wall element consisting of a body threaded at one end and provided with an upstanding non-circular stud, and a shade engaging element comprising a bracket having a plurality of correspondingly non-circular sleeves adapted selectively to fit over said stud, said sleeves being adapted to interfit with said stud in either of two positions substantially at right angles to one another.
5. In a shade support, a wall element consisting of a body threaded at one end and provided with an upstanding non-circular stud, and a shade engaging element comprising a bracket integral with a plurality of correspondingly non-circular sleeves adapted selectively to fit over said stud, said sleeves being adapted to interfit with said stud in either of two positions substantially at right angles to one another, and said sleeves being arranged in a linear series.
6. In a shade support, a wall element consisting of a body threaded at one end and provided with an upstanding non-circular stud, and a shade engaging element comprising a bracket integral with a plurality of correspondingly non-circular sleeves adapted selectively to fit over said stud, said sleeves being adapted to interfit with said stud in either of two positions substantially at right angles to one another, and said sleeves being arranged in a linear series extending substantially at right angles to said bracket.
7. In a shade support, a means for supporting each end of a shade roller from a single screw by a means comprising a squared upstanding stud, a shade engaging bracket provided with means for supporting a curtain rod and comprising a series of sleeves for selective reception of said stud, permitting independent adjustment either of said bracket or of said curtain rod.
8. In a curtain support the combination of a longitudinal adjustable rod terminating in a downwardly projecting stud, a shade bracket provided with a series of vertical sleeves for selectively receiving said stud and a wall member having an upwardly projecting stud, angular in cross section, to fit selectively into one of said sleeves in non-rotative relation thereto.
- In testimony whereof I have signed my name to this specification.

MADS M. LARSEN.
